UNITED STATES PATENT OFFICE

128,478

DESIGN FOR A LIGHTING FIXTURE

Thomas A. Carter, Jr., Grand Rapids, Mich., assignor to Grand Rapids Store Equipment Company, Grand Rapids, Mich., a corporation of Michigan

Application May 19, 1941, Serial No. 101,008

Term of patent 7 years

To all whom it may concern:

Be it known that I, Thomas A. Carter, Jr., a citizen of the United States, residing at Grand Rapids, in the county of Kent and State of Michigan, have invented a new, original, and ornamental Design for a Lighting Fixture, of which the following is a specification, reference being had to the accompanying drawing, forming part thereof.

Fig. 1 is a perspective view of the lighting fixture showing my new design as it would appear attached to the ceiling of a room.

Fig. 2 is a partial cross-sectional view of the same, taken along the line 2—2 in Fig. 1.

The side and end of the fixture not shown in the perspective view are duplicates of those which are shown.

I claim:

The ornamental design for a lighting fixture, as shown and described.

THOMAS A. CARTER, JR.
